UNITED STATES PATENT OFFICE.

ANDREW BRUNTON, OF CHICAGO, ILLINOIS.

MEANS FOR HOLDING SASH IN POSITION.

1,050,801.

Specification of Letters Patent. Patented Jan. 21, 1913.

Application filed March 27, 1912. Serial No. 686,693.

To all whom it may concern:

Be it known that I, ANDREW BRUNTON, a citizen of the United States, residing at Chicago, in the county of Cook and State 5 of Illinois, have invented new and useful Improvements in Means for Holding Sash in Position, of which the following is a full, clear, concise, and exact description, reference being had to the accompanying drawing, forming a part of this specification.

My invention relates to improvements in window supports and has for its object the production of a device by means of which a 15 swinging sash or window may be yieldingly held in any desired open position or locked in position when closed.

A further object is the production of a simple device by the use of which the window or sash may be held open to any desired 20 degree and also permitting it to be shifted into other positions without disturbing the retaining means.

A further object is the production of a simple and efficient device, cheaply manufactured, and attached to any window or sash and one not liable to disarrangement of parts.

These and such other objects as may hereinafter appear are attained by my device, 30 embodiments of which are illustrated in the accompanying drawings, in which—

Figure 1 represents a front view of a transom equipped with my improvement; Fig. 2 represents a side elevation of Fig. 1; Fig. 3 represents a sectional view of the sash and frame showing wings or brackets; Fig. 4 represents a sectional view on the line 4—4 of Fig. 1, looking in the direction indicated by the arrows; Fig. 5 is a side elevation 40 of a portion of Fig. 1, showing the transom closed; Fig. 6 represents a sectional view on the line 6—6 of Fig. 5, looking in the direction indicated by the arrows; Fig. 7 represents an end view of Fig. 8; Fig. 8 represents an enlarged front elevation showing a portion of Fig. 1 with a lower fastening device; Fig. 9 represents a side elevation 45 of Fig. 8; Fig. 10 represents a sectional detail showing a modification; and Fig. 11 represents a sectional view on the line 11—11 of Fig. 1.

Like numerals of reference indicate like parts in the several figures of the drawings.

I have illustrated my device in connection 50 with a transom, hinged at the bottom, and in Figs. 1 and 2 the numeral 12 represents

the frame; 13 the sash and 14 the pane of glass. The sash is provided with a pair of bottom hinges permitting the upper portion of the transom to swing outwardly and 60 downwardly.

The sash is held normally closed by any suitable locking means, such for instance as a spring bolt 16 on the sash adapted to lock into the socket 17 on the frame. At its 65 lower end the bolt is provided with an ordinary gripping ring 18 by means of which the bolt can be withdrawn and the transom opened in the usual manner.

On either or both sides of the transom I 70 provide frictional retaining means, by means of which the sash may be kept in any desired position, comprising broadly a swinging supporting bar 19 pivotally mounted at its upper end on a bolt 20 in the 75 upturned ear or flange of a bracket 21 mounted on the frame. The bar or brace 19 is interiorly slotted throughout the greater portion of its length, as shown at 22, the sides of the slot being either smooth, as 80 shown at 22^a (Fig. 9), or notched, as shown in Fig. 2. On the face of the sash is mounted an ear or bracket 23 provided with a pocket 24^a in the bottom of which is screwed a bolt 24 surrounded by a spring 25. The outer end of the bolt passes through the slot 22 in the bar 19 and washers 26, 26^a are mounted on the bolt on either side on the face of the bar; the head 27 of the bolt holding the parts securely in place. The 85 spring is normally under compression so as to force the washer 26 against the inner face of the bar 19, frictionally holding it in any desired position.

When the transom is closed the bar 19 fits 90 snugly against the side of the sash and is locked in position by means of a latch 28, the hooked end 29 of which enters an opening or socket 29^a in the frame through an opening 30 in the plate 31 secured to the frame over the socket. The bar is held in place by pulling up the end or handle 32 of the latch, bringing the hook 29 into engagement with the under face of the plate 31, as shown at 33.

In order to insure the smooth action of the bar and prevent it striking or binding against the sash or frame in closing the transom, I provide a pair of guiding wings or brackets 34, 34^a secured opposite each other on the sash and frame, having their upwardly inclined flanges set at a slight 105 110

angle to the line of travel of the bar, forming, as it were, a throat or opening 35 through which the bar is guided accurately into closed position.

5 In Figs. 7 and 8 I have illustrated a modified means of locking the transom when closed, comprising a plate 36 secured to the sash in any suitable manner and on which is pivotally mounted a catch or latch 37 ending in a handle 38. This latch is mounted to swing into the slot 39 in a bracket 40 mounted on the sash and to also fit within the slot or notch 40^a in the end of the bar 19. As clearly shown in Fig. 8, the bar may be 15 positively locked when the transom is closed by swinging the latch 37 into locking position.

It is, of course, evident that instead of 20 mounting the bracket on the sash to receive the bolt I may provide means for fitting the bolt in the side of the sash itself, as shown on the left in Fig. 1, and an improved form of such means is shown in detail in Fig. 11 in which a socket 41 having a peripheral 25 flange 42 is fitted into a hole 43 bored or sunk into the sash. The socket 41 has in the center of its bottom a hole adapted to receive the end of the screw bolt 24. It will be noted that the end 24^a of the bolt is extended and adapted to be screwed into the sash itself. A covering box 44 surrounds the spring and fits snugly within the inner periphery of the socket 41, the top 45 serving as a rest for the top of the spring and 35 also taking the place of the inner washer 26 in the other form. In this form of device the parts are protected from the weather and are much less liable to rust or get out of order.

40 It is to be noted that while I have shown different forms of device on the same figure in the drawing, it is not intended to use such forms in actual practice as, of course, in using the devices the same style will be 45 used on both sides of the sash or frame, both with respect to the friction-holding device and also the locking device for securing the bar in closed position.

Heretofore great difficulty has been experienced with opening transoms, windows and doors and keeping them open any predetermined distance, especially in the case of transoms or cellar windows in which the window is frequently opened part way and 50 a stick inserted, resting on the frame and against the sash, the result being that the stick is frequently knocked out, the window dropping against the frame, thus breaking the glass. A similar difficulty is experienced 55 with transoms or upper windows, especially those used in halls and lodge rooms, requiring the use of a long pole with a hooked end, which is adapted to engage and unlock the retaining bolt, permitting the window to be pulled down. With this device

attached the window can be pulled down to any desired distance and held frictionally in place, the compression of the spring 25 being arranged to meet existing circumstances, that is, in the case of large windows 70 the spring will be made heavier and longer so as to exert lateral pressure against the bars, especially if the window is to be pulled down and outwardly. In the event that it is to be used with windows opening side- 75 wise a lighter spring could be used as less friction would be required to hold the window or door in place.

All of the forms shown involve very simple construction but they are of such a nature as to accomplish valuable results that have not heretofore been attained by any of the devices now in use.

It is, of course, clearly understood that other forms of construction or material may 85 be used to accomplish the same result without departing from the spirit of my invention.

I claim:

1. In a device of the character described, 90 the combination with a frame, a sash, a slotted supporting bar swingingly mounted on said frame, a bolt passing through the slot in said bar and engaging said sash, a spring normally under compression 95 mounted within said sash and surrounding said bolt and bearing against the face of said bar.

2. In a device of the character described, 100 the combination with a frame, a sash, a slotted supporting bar swingingly mounted on said frame, frictional engaging means mounted on said sash comprising a socket fitting in or on said sash, a bolt passing through the slot in said bar and into said socket, a spring normally under compression 105 mounted in said socket and surrounding said bolt and adapted to bear against the inner face of said bar.

3. In a device of the character described, 110 the combination with a frame, a sash, a slotted supporting bar swingingly mounted on said frame, frictional engaging means mounted on said sash comprising a socket fitting in or on said sash, a bolt passing 115 through the slot in said bar and into said socket, a spring normally under compression mounted in said socket and surrounding said bolt, a cap fitting within said socket and surrounding said spring, the compression of said spring forcing said cap against 120 the inner face of said bar.

4. In a device of the character described, 125 the combination with a frame, a sash, a slotted supporting bar swingingly mounted on said frame, frictional engaging means mounted on said sash comprising a socket fitting in or on said sash, a bolt passing through the slot in said bar and into said socket and screwed into said sash, a spring 130

normally under compression mounted in said socket and surrounding said bolt and adapted to bear against the inner face of said bar.

- 5 5. In a device of the character described, the combination with a frame, a sash, a slot-ted supporting bar swingingly mounted on said frame, a bolt passing through the slot in said bar and engaging said sash, a spring 10 normally under compression mounted within said sash and surrounding said bolt and bearing against the face of said bar, and

means mounted on said sash and adapted to engage means mounted on said frame and also to engage said bar, thereby locking said 15 sash in closed position.

In witness whereof, I have hereunto subscribed my name in the presence of two witnesses.

ANDREW BRUNTON.
